UNITED STATES PATENT OFFICE.

CARLYLE W. THOMAS AND FREDERICK E. BRADLEY, OF BRIDGEPORT, CONNECTICUT,
ASSIGNORS TO THE SINGER MANUFACTURING COMPANY, A CORPORATION OF NEW
JERSEY.

STITCHING AND RUFFLING MACHINE.

1,320,185.

Specification of Letters Patent.

Patented Oct. 28, 1919.

Application filed July 3, 1917. Serial No. 178,337.

To all whom it may concern:

Be it known that we, CARLYLE W. THOMAS and FREDERICK E. BRADLEY, citizens of the United States, residing at Bridgeport, in the county of Fairfield and State of Connecticut, have invented certain new and useful Improvements in Stitching and Ruffling Machines, of which the following is a specification, reference being had therein to the accompanying drawings.

This invention relates to improvements in sewing machines for guiding ruffling and stitching fabrics and has for its object to lessen the operations necessary for effecting certain of such products, to provide a more desirable and conveniently manipulated construction, to combine a duplex ruffling mechanism with a single organized stitch-forming and cloth-feeding mechanism and in a manner to give to the products, by a single operation, a more slighted and elaborate effect than is possible in connection with the earlier art.

It is believed that the present improved means is the first to produce by a single operation of a single organized stitch-forming and cloth-feeding mechanism separately directed like or unlike strips of seam secured ruffed fabrics, which improved means carries with it features in construction making it convenient to greatly vary the character of the product, all of which will appear more fully from the following description and claims when considered in connection with the accompanying drawings, in which Figure 1 is a view in front side elevation of the front end portion of one form of commercial sewing machine supplied with the present invention. Fig. 2 is a view in front end elevation of Fig. 1. Fig. 3 is a view in sectional elevation of Fig. 1, looking in the direction indicated by the arrow S. Fig. 4 is an inverted plan view taken in the plane A, B, Fig. 1. Fig. 5 is a view in perspective of one of the ruffling blades, together with its adjusting means and the means for connecting it with its operating shaft. Fig. 6 is a view in perspective of the cloth-presser and its attached tape-guide. Fig. 7 is a view in perspective of the fabric-guide. Fig. 8 is a view partly in section of the radially projecting lever and radially projecting crank-arm for transmitting movements to the outer of the two ruffling members, together with pivot block and coupling. Fig. 9 is a view in

cross section of the inner radially projecting lever for transmitting movements to the inner of the two members, together with adjustable stop block. Fig. 10 is a view of telescopically arranged ruffling blade actuating shafts. Fig. 11 is a view of one variety of product effected by the present invention.

The present invention is shown and will be described as applied to one form of Singer commercial sewing machine, but as it relates only to the construction and application of a multiple ruffling mechanism, only such reference will be made to the other elements of the machine as is deemed necessary for a proper understanding of its application.

Referring to the figures, 1 represents the main- or needle-bar actuating shaft journaled in suitable bearings formed in the bracket-arm 2, carried by the cloth-plate 2', the latter and said bracket-arm comprising the sewing machine frame, 3 an eccentric suitably secured on said shaft and encircled by an eccentric strap 4 of an eccentric connection 5 having its lower end fulcrumed on a stud 6 threaded into a radially projecting crank-arm 7 suitably secured upon the inner end of a short shaft 8 journaled in a suitable bearing formed in a bracket 9 secured by screws, as 10, to the bracket-arm 2.

11 represents a tubular ruffling blade actuating shaft and 12 a shaft loosely mounted in said tubular shaft, the latter having suitably secured upon its inner end a radially projecting lever 13 provided with a slot 14 (see Fig. 9) into which is slidably mounted an adjustably secured stop block comprising the block 15, washer 16 and screw 17, the latter threaded into said block, and an adjustably secured pivot block 18 substantially the same as shown in Fig. 8, later to be referred to, and 19 a U-shaped bracket, one arm of which is permanently secured to the crank-arm 7 and the other to the lever actuating crank-arm 20 provided with a groove 21. 22 denotes a second radially projecting lever having a slot 23 in which is slidably mounted a stop block 24, the same as that shown in Fig. 9, and an adjustably secured pivot block 24' comprising a flanged block 25 provided with a teat or pin 26 entering the slide block 27 in the groove 21, the opposite side of said flanged block being provided with a threaded projection 28, shown in dotted lines only, Fig. 8, and onto said

projection is threaded a winged nut 29 and beneath the latter a washer 30, and below said washer an indexing plate 31, the nut 29 acting to secure said pivot block against 5 accidental movement in the slot 23, the pivot block 18 being of like construction except that in the latter the crank-pin 32 is employed instead of the wing 33 of the nut 29 and the groove 14' carries a block, shown in 10 dotted lines, Fig. 4, corresponding to block 27 shown in Fig. 8.

As the means for operatively connecting the ruffling blades 34 and 35 with their respective actuating shafts 12 and 11 comprise 15 a like combination of elements it is deemed sufficient to refer only to the connections for operating the ruffling blade 34.

36 represents a shaft crank suitably secured upon the ruffling blade actuating shaft 20 12 and to said shaft crank is adjustably secured by screws, as 37, a blade actuating lever 38 provided with a pivotally secured blade carrying bracket 39 to which is suitably secured the ruffling blade 34, said 25 bracket having formed integral with it a finger piece 40 having an opening 41 through which extends a threaded rod 42 suitably secured in a projection 43 carried by the lever 38, said rod having threaded upon it a 30 nut 44 the adjustment of which causes the spring 45 to act on said finger piece to effect the desired downward pressure of the blade 34. 46 represents a horizontally arranged finger projecting from the bracket 39 the 35 free end of which lies directly over the bent end portion 47 of the blade lifting arm 48 carried by the cloth-presser carrying bar 49 to, when the latter is elevated by common means including the present lifting lever 50, 40 effect a rocking movement of the bracket 39 and raise the ruffling blade 34 to accommodate the manual manipulation of the fabric being acted on. From the foregoing is to be understood that rocking movements are 45 transmitted from the main-shaft 1 to the crank-arms 7 and 20 through the eccentric 3 and connection 5 and that such movements are transmitted to the levers 13 and 22 through the pivot blocks 18 and 24' respectively, and that the amplitude of rocking 50 movement transmitted to the respective shafts 11 and 12, and accordingly, to the respective ruffling blades 35 and 34 depends upon the adjustments of the pivot blocks 18 and 24' with respect to the axes of the 55 respective shafts 11 and 12.

51 represents a tape or band-guide carried by the cloth-presser 52 and in the present instance shown as a tape folding and 60 guiding element through which the band or covering-strip 53 (see Fig. 11) is passed from the supply to the action of the needles and may be construed with or without the folding scrolls, as 54, dependent upon 65 whether a selvage or raw edged tape or band

is to be employed. 55 represents a fabric guide bracket secured by screws, as 56, to the bracket 9 and carrying at its lower end a base-plate 57 upon which is secured by screws, as 58, left and right hand edge-guides 59 and 60 respectively, and to the underside of said plate is secured by screws, as 61, a separator-blade 62 of a length and width to underlie the ruffling blades, as more clearly shown in Fig. 3. 75

In effecting the product illustrated the body-fabric 63 is passed between the throat or needle-plate 64 and the separator blade 62, and the trimming fabric 65 through the edge-guide 60 and the lace trimming 66 80 through the guide 59.

Having thus set forth the nature of the invention, what we claim herein is:—

1. In a machine for stitching and separately ruffling multiple fabrics, the combination with a machine frame comprising a lower member provided with a permanently secured upper member in which is journaled a main-shaft, a stitch-forming mechanism including a needle carrying bar provided with a needle and operatively connected with said main-shaft, a fabric-feeding element and means for actuating the latter, of a ruffling mechanism including a tubular rock-shaft carrying a ruffling member and journaled in a suitable bearing carried by said upper frame member, a rock-shaft journaled in said tubular rock-shaft and provided with a second ruffling member and connections between the main-shaft and said rock-shafts for giving to said ruffling elements fabric ruffling movements. 90 95

2. In a machine for stitching and separately ruffling multiple fabrics, the combination with a machine frame comprising a base member carrying a bracket-arm in which is journaled a main-shaft, a stitch-forming mechanism including a needle carrying bar provided with a multiple of needles and operatively connected with said main-shaft, a fabric feeding element and means for actuating the latter, of a ruffling mechanism including a tubular rock-shaft journaled in a suitable bearing carried by said bracket-arm and a rock-shaft journaled in said tubular rock-shaft, each of said rock-shafts being provided, at one end, with a ruffling mechanism and at the opposite end of each with a radially projected lever and a second rock-shaft provided with a radially projecting crank-arm operatively connected with said levers and with said main-shaft for transmitting from the latter to said ruffling elements fabric ruffling movements. 110 115 120

3. In a machine for producing seam-sealed ruffled fabrics, the combination of a single machine frame comprising a base member provided with a single bracket-arm unsupported at its free end in which is journaled a main-shaft, a stitch-forming mecha- 125 130

nism including a needle carrying bar provided with a multiple of needles and operatively connected with said main-shaft, a single fabric feeding mechanism and means 5 for actuating the latter, a ruffling mechanism including a multiple of ruffling members actuated from said main-shaft and means for directing the fabric to the action of the stitch-forming, cloth-feeding and ruffling 10 mechanisms including horizontally arranged fabric guides arranged below said ruffling members and supported by said bracket-arm.

4. In a machine for producing seam-sealed ruffled fabrics and for uniting the same to separate plies of fabrics, the combination of a single machine frame comprising a base member provided with a single bracket-arm in which is journaled a main-shaft and in which is mounted to move ver-

tically a cloth-presser carrying bar provided with a cloth-presser, a stitch-forming mechanism including a needle carrying bar provided with multiple needles and operatively connected with the main-shaft, a single fabric feeding mechanism and means for actuating the latter, a ruffling mechanism including a multiple of ruffling members actuated from said main-shaft and means for directing the fabric to the action of said stitch-forming, cloth-feeding and ruffling mechanisms including horizontally arranged fabric guides arranged below said ruffling members, together with a band-guide carried by said cloth-presser carrying bar.

In testimony whereof we have signed our names to this specification.

CARLYLE W. THOMAS.
FREDERICK E. BRADLEY.
